UNITED STATES PATENT OFFICE.

WILLIAM C. OSTERHOLM, OF CHICAGO, ILLINOIS, ASSIGNOR TO INTERNATIONAL HARVESTER COMPANY OF NEW JERSEY, A CORPORATION OF NEW JERSEY.

HYDROCARBON-BURNER.

1,175,075.

Specification of Letters Patent. Patented Mar. 14, 1916.

Application filed July 31, 1913. Serial No. 782,352.

To all whom it may concern:

Be it known that I, WILLIAM C. OSTERHOLM, a citizen of the United States, residing at Chicago, in the county of Cook and State of Illinois, have invented certain new and useful Improvements in Hydrocarbon-Burners, of which the following is a full, clear, and exact specification.

My invention relates to hydrocarbon burners, and in its present form is especially adapted for burning low grade liquid fuels, such as tar.

It is my object to effect an economy in burners of this class by providing a device capable of burning extremely low grade viscous fuels, and in which the use of steam and expensive agents for treating and atomizing fuel may be obviated.

A further object is to produce a burner of greater heating capacity than has been possible heretofore in devices of this class by providing for a thorough atomization of the tar or other fuel, and also by providing improved means for spreading the flame to thereby increase its area.

It is also my object to render more efficient a burner of this type by providing for the regulation of the amount of fuel delivered to the burner, to thereby increase or diminish the intensity of the heat thrown off by the flame. And finally, it is my object to produce certain improvements in the arrangement and combination of the various parts of such a device, whereby a simple and economical construction will result.

The foregoing and other objects and advantages of my improved construction will become readily apparent from the following detailed description of one form of my invention illustrated in the accompanying drawing, in which—

Figure 1 shows a vertical central sectional view of my device as applied to a furnace or heating chamber; Fig. 2 shows a rear end view, partly in elevation and partly in section, of the device shown in Fig. 1; Fig. 3 shows a detail view of the means employed in my device for varying the speed of the fuel feeding mechanism; and Fig. 4 shows a detail view of the means employed for insuring a uniform delivery of the fuel by the conveyer to the atomizer and injector.

Generally speaking, the construction shown comprises a fuel conveyer and driv-

ing mechanism therefor; a fuel supply system; and a fuel atomizer and injector.

The conveyer comprises an endless chain 10 carried upon rollers or sprocket wheels 11 mounted upon shafts 12, which shafts are journaled in the sides of a fuel receptacle 13 surrounding the conveyer. For driving the conveyer I employ a friction disk 14 mounted upon the outwardly projecting end of the upper shaft 12. A frictional driving member 15 is arranged adjacent to the disk 14 and in engagement therewith, and is slidably and non-rotatably mounted upon a vertical shaft 16. On the lower end of said shaft 16 is a worm gear 17 in mesh with an endless screw 18 upon the armature 19 of a motor 20 which is the source of driving power.

For varying the speed at which the frictional disk 14 and upper shaft 12 are driven, I provide a bracket 20 embracing upper and lower surfaces of the frictional driving member, said bracket being slidably mounted in a supporting casing 21 and held in any adjusted position by means of a set screw 22 operating in a slot 23. It will thus be seen that by moving the bracket 20 within the limits allowed by the slot 23, the driving member 15 will be moved longitudinally on its shaft 16 and in this way the point at which the driving member engages the driven member can be varied to suit the necessary speed requirements.

For supplying fuel to the receptacle 13 I have provided a float valve chamber 24, within which is carried a float 25 controlling an inlet valve 25^a for establishing communication between a fuel supply pipe 26 and the valve chamber. Communication between the valve chamber and fuel receptacle is provided for by the employment of a pipe 24^a. By this arrangement I am able to maintain a substantially constant level of the fuel within the receptacle 13.

Obviously, with the lower portion of the fuel conveyer submerged in a body of tar or other viscous fuel within the receptacle 13, the conveyer, when operated, will carry with it particles of fuel to the top thereof and at this point I have provided the following means for atomizing the fuel and injecting it into a chamber, or other desired place, for combustion: A blast pipe 27, having its discharge end constricted and fixed

- adjacent to the upper end of the fuel conveyer, is connected with a source of compressed air supply and arranged in such a manner that air is directed tangentially along the upper arc of the conveyer with such force that fuel contained thereon will be carried away with and atomized by the blast of air. A conduit 28 fixed in a removable cap 28' screwed into the receptacle 13, is arranged adjacent to the upper end of the conveyer and has one of its ends surrounding the discharge end of the blast pipe. The opposite end of said conduit is preferably beveled, and surrounding the beveled end thereof is a burner tip 29, also beveled, and so arranged that an annular opening 29^a is formed between the adjacent ends of the burner tip and conduit. The other end of the burner tip communicates with a furnace or other heating chamber 30.
- From what has been said, it is obvious that the blast of air from the pipe 27 will be directed through the conduit 28 and burner tip 29 into the furnace or chamber, and in passing over the upper end of the fuel conveyer, it will carry with it and become thoroughly commingled with the fuel that is contained thereon, and thus produce a combustible mixture.
- For more thoroughly atomizing the fuel and for spreading it to increase the area of the flame, I have provided the following means: An annular air chamber 31 is arranged preferably upon the furnace 30 and surrounds the burner tip 29 and a portion of the conduit 28. This chamber is in communication with a pipe 32 connected with a source of air supply of considerably less pressure than that supplied to the blast pipe 27. A casing 33 formed on the fuel receptacle 13, preferably integrally therewith, projects within the air chamber 31 and surrounds the adjacent coöperating ends of the conduit 28 and burner tip 29, forming at the same time bearings for these parts. A series of openings 34 is provided in the sides and upper portion of this casing adjacent to the coöperating ends of the conduit and burner tip. Air is admitted through these openings 34 from the air chamber and passes into the burner tip through the annular opening 29^a formed between said tip and conduit. Owing to the beveled arrangement of the adjacent ends of the burner tip and conduit, it will be seen that air passing through the opening 29^a enters the burner tip in forwardly converging lines and in this way it becomes thoroughly commingled with the fuel from the conveyer and a more thorough atomization of said fuel results. The outer end of the casing 33 is beveled, as is also the adjacent end of the air chamber, and by spacing the end of the casing apart a slight distance from the beveled end of the air chamber, an annular opening 36 is formed

which admits air from the air chamber across the discharge end of the burner tip and into the furnace in cross directions. In this way the combustible fuel from the burner tip is spread evenly in all directions, and thereby a considerably increased area of the flame will result.

The lower portion of the casing 33, it will be seen, is not provided with the perforated openings 34, as are the upper and side portions, so that any fuel which may collect upon the sides of the burner tip will pass downwardly through the annular opening 29^a and into the casing, from where it will be delivered back into the fuel receptacle through a by-pass 37 formed in the receptacle for that purpose.

For regulating the quantity of fuel delivered by the conveyer for a given speed, I have provided the following: A screw-threaded shaft 38 passing through the side of the receptacle has fitted to its inner end a roller 39, and on its outer end is provided with an adjusting nut 40. This shaft is non-rotatably journaled in a bearing 41 formed on the receptacle and by turning the nut, the shaft is moved in either direction to the desired position. Thus, during periods of low temperature, the roller 41 can be moved close to the conveyer and heavy lumps of tar will thereby be removed. Also, by having the position of the roller adjustable, the size of the flame can be controlled through the regulation of the fuel.

While I have shown and described but one form of my device, it will be understood, nevertheless, that it is capable of many modifications and that changes may be resorted to in the arrangement and construction thereof without departing from the spirit of my invention as disclosed in the appended claims.

What I claim as my invention and desire to secure by Letters Patent is:—

1. In a burner, the combination of a fuel conveyer, a blast pipe arranged to direct a current of air into said fuel for the purpose of delivering the same into a combustion chamber, a conduit to receive the blast of fuel and air, a burner tip for said conduit, said burner tip and conduit being provided with an opening, and an air chamber arranged to direct a current of air through said opening and also to direct a current of air across the discharge end of said burner tip.

2. In a burner, the combination of a fuel receptacle, a flexible conveyer for the fuel, means for operating said conveyer, and means for directing a supporter of combustion into the fuel on said conveyer and delivering it into a chamber for combustion purposes.

3. In a burner, the combination of a fuel receptacle, an endless conveyer partly sub-

merged in the fuel in said receptacle, means for operating said conveyer, and a blast pipe arranged to direct a current of combustion supporter tangentially along said conveyer for the purpose of atomizing and carrying the fuel thereon to a point distant for combustion purposes.

4. In a burner, the combination of a fuel receptacle, an endless conveyer partly submerged in the fuel in said receptacle, means for operating said conveyer, and a blast pipe arranged to direct a current of air tangentially along the surface of said conveyer for the purpose of removing the fuel therefrom and delivering it to a combustion chamber in an atomized state.

5. In a burner, the combination of a fuel receptacle, an endless conveyer partly submerged in the fuel in said receptacle, means for operating said conveyer at variable speeds, and means for removing the fuel from said conveyer and delivering it in an atomized state to a chamber for combustion purposes.

25 6. In a burner, the combination of a fuel receptacle, an endless conveyer having one end submerged in the fuel in said receptacle, means for operating said conveyer, means for effecting a uniform delivery of the fuel, and means for directing a current of air on said conveyer for the purpose of removing the fuel therefrom and delivering it in an atomized state to a chamber for combustion purposes.

35 7. In a burner, the combination of a fuel receptacle, an endless conveyer therein having one end submerged in the fuel in said receptacle, wheels for said conveyer, shafts for said wheels, a frictional driven member on one of said shafts, a frictional driving member in engagement with said driven member, means for sliding said driving member to thereby vary the speed of the driven member, and means for delivering the fuel from said conveyer in an atomized state into a chamber for combustion purposes.

8. In a burner, the combination of a fuel receptacle, a fuel conveyer in said receptacle, means for operating said conveyer, means for maintaining a substantially constant level of fuel in said receptacle, and means for removing fuel from said conveyer and delivering it in an atomized state into a chamber for combustion purposes.

55 9. In a burner, the combination of a fuel receptacle, a fuel conveyer in said receptacle, a float valve chamber in communication with said receptacle, a fuel supply for said chamber, a float valve for controlling communication between said supply and

valve chamber, means for operating said conveyer, and means for removing fuel therefrom and atomizing it for combustion purposes.

10. In a burner, the combination of a fuel receptacle, a fuel conveyer for said receptacle, a blast pipe arranged to direct a current of air into the fuel on said conveyer, a conduit to receive the blast of air and fuel from said conveyer, a burner tip arranged at the end of said conduit forming an opening between said conduit and tip, and a casing surrounding said conduit and burner tip and communicating with said fuel receptacle for the purpose of returning overflow fuel from said burner tip to the fuel receptacle.

11. In a burner, the combination of a fuel receptacle, a conveyer therefor, means for operating said conveyer, a blast pipe arranged to direct a current of air into the fuel on said conveyer, a conduit to receive the blast of air and fuel from the conveyer, a burner tip surrounding the end of said conduit and spaced apart therefrom, a casing surrounding said conduit and burner tip and provided with openings in its sides and upper portion, an air chamber surrounding said casing and arranged to direct a current of air through the openings in said casing and into said burner tip, and also to direct a current of air across the discharge end of said burner tip, said casing being in communication with said fuel receptacle and arranged to receive overflow fuel from said burner tip and deliver it back to said receptacle.

12. In a burner, a receptacle to contain fuel, a fuel conveyer, means for operating the conveyer, adjustable means coöperating directly with the conveyer for regulating the amount of fuel delivered by said conveyer, and means for removing the fuel from the conveyer and atomizing it for combustion purposes.

13. In a burner, a receptacle to contain fuel, a fuel conveyer within said receptacle, a movable member carried within said receptacle adjacent to the conveyer and provided with adjustable means on the exterior of said receptacle for regulating the amount of fuel delivered by said conveyer, and means for atomizing the fuel and removing it from the conveyer for combustion purposes.

In testimony whereof I affix my signature, in the presence of two witnesses.

WILLIAM C. OSTERHOLM.
